METHOD AND APPARATUS FOR DEFLECTION DRILLING Wayne A. Smithson, 2865 Torito Road, Montecito, Calif.
Filed Mar. 1, 1963, Ser. No. 262,051
8 Claims. (Cl. 175—61)

This invention relates generally to a method and apparatus for deflection drilling and more particularly to a novel whipstock and method of using the same for directional drilling in oil well bore holes.

In conventional deflection drilling operations, a tool known as a "whipstock" is used. This whipstock comprises an elongated tubular section having a tapered sidewall or wedge and upper collar portion, the part of the tube opposite the sidewall wedge being open. The arrangement is such that the collar portion of the whipstock may be secured about the end of a drill pipe string and the whipstock lowered into a bore hole. The whipstock is then set in a desired position such that it will cam the drilling bit body and drill bit to one side thereby forming a deflected hole, commonly referred to as a "rathole."

Since the drill bit employed for forming the rathole is necessarily smaller in diameter than a conventional drilling bit in order that it may pass through the whipstock collar, the "rathole" itself is of smaller bore diameter. Thus, to commence drilling in the rathole with conventional drilling equipment, it is first necessary to "ream out" or enlarge the diameter of the rathole. Accordingly, after the "rathole" has been drilled for a certain distance, the drill pipe string is raised along with the whipstock and a reaming tool is then inserted on the end of the drill pipe string. The drill pipe string is then lowered into the bore hole and the reaming tool will ream out the rathole to normal size. The drill pipe string is then raised again to the surface and conventional drilling equipment substituted for the reaming tool. Drilling in the direction of the deflected hole can then proceed in the usual manner.

From the foregoing, it will be evident that when a conventional whipstock is used, the drill pipe string must be pulled out of the bore hole several times to change the drill bit to a smaller drill bit, then to a reamer tool, then back to the conventional drill bit. Pulling the entire drill pipe string from a bore hole especially a deep hole of the order 6,000 or 7,000 feet is extremely time consuming and thus very costly to oil well operators.

With the foregoing in mind, it is accordingly a primary object of the present invention to provide a novel deflection drilling method and apparatus in which a deflected hole or "rathole" may be reamed immediately after the drilling of the "rathole" without the necessity of removing the drill pipe string, to the end that one complete round trip in and out of the bore hole is avoided.

Another object of this invention is to provide an improved orienting method and means usable with the novel whipstock structure of this invention for facilitating the orientation of a whipstock so that a deflected hole may be initiated in a desired direction.

Briefly, these and many other objects of this invention are attained by employing the whipstock itself as a reaming tool so that after a "rathole" has been formed, the whipstock which is already in the bore hole may be used as the reaming tool for reaming out the deflected bore. By this arrangement, raising the entire drill pipe string to attach a conventional reaming tool is avoided.

The method of the invention thus contemplates the steps of lowering a whipstock secured to a drill bit body and drill bit on the end of a drill pipe string to a given position in a bore hole; releasing the drill bit body from the whipstock so that drilling may progress through the whipstock in a deflected manner to form a deflected bore; retracting the drill bit body and drill bit sufficiently to reengage the whipstock; and, then drilling the deflected bore with the whipstock itself as the drilling tool. Further

2

steps of the method include controlling fluid flow to pass through the conventional drill bit body when the whipstock is being employed to cam the drill bit body and drill bit in a direction to form the deflected bore and diverting this flow to pass through the whipstock when the whipstock is being used as a drilling tool. The invention also contemplates an orienting step in combination with the foregoing steps so that the deflected bore or rathole may be deflected in a desired direction.

10 The preferred apparatus for carrying out the foregoing method includes a novel whipstock structure including a drilling fluid passage formed in the whipstock itself to pass drilling fluid to cutting wheels disposed on the whipstock adjacent its lower end. The whipstock also includes first 15 and second locking means for securing the whipstock to the drill bit body for longitudinal movement with the drill bit body. Also provided are coupling means for preventing relative rotation between the whipstock tool and the drill bit body so that the whipstock tool may be rotated by the drill bit body when the whipstock is being used as a reaming tool.

20 In the operation of the apparatus, the whipstock is secured to the drill bit body by the first locking means until it is properly oriented and set in a desired position in the bore hole. The first locking means is then released and the deflected drilling can take place with the whipstock guiding the drill bit as is presently done. The drill bit body is then retracted and caused to re-engage the whipstock by means of the second locking means and then the entire 25 whipstock structure is rotated with the drill bit body to ream out the deflected bore or rathole. When the reconnection is made between the drill bit body and whipstock, a fluid flow control means in the drill bit body diverts drilling fluid to the passage in the whipstock so that the cutting wheels on the whipstock will be properly lubricated and serve to carry debris to the surface of the bore hole 30 during the reaming out of the rathole.

35 A better understanding of the foregoing method and apparatus will be had by now referring to the accompanying drawings, in which:

40 FIGURE 1 is a side elevational view of the improved whipstock tool of this invention disposed within a bore hole, shown in cross section, preparatory to a deflection drilling operation;

45 FIGURE 2 is a cross section taken in the direction of the arrows 2—2 of FIGURE 1;

50 FIGURE 3 is a view similar to FIGURE 1 illustrating the apparatus for forming a deflected bore or "rathole" in accordance with one of the steps of the method;

55 FIGURE 4 illustrates a further step in the method wherein the whipstock has been re-engaged by the drill bit body and itself is being employed as a reaming tool;

FIGURE 5 illustrates a subsequent whipstock position and drill bit body when the whipstock is used as a reaming tool;

60 FIGURE 6 is an enlarged fragmentary view partly in cross section of the drill bit body and whipstock tool when in the relative positions illustrated in FIGURE 1;

FIGURE 7 is an enlarged fragmentary view of a 65 fluid flow control means illustrating the relative positions of components when the drill bit body is in the position illustrated in FIGURE 3;

FIGURE 8 is a view similar to FIGURE 6 illustrating the relative positions of the whipstock tool and drill bit body corresponding to those shown in FIGURE 4; and,

FIGURE 9 is a cross section taken generally in the direction of the arrows 9—9 of FIGURE 6.

Referring first to FIGURE 1, there is shown at the 70 upper end of the drawing an oil well bore hole 10 within which there is positioned a whipstock 11. The whipstock 11 is arranged to be lowered on the end of a

drill pipe string 12 terminating in a drill bit body 13 shown in dotted lines within the collar of the whipstock. The lower end of this drill bit body 13 includes a drilling bit 13', similarly shown in dotted lines. The whipstock 11 is secured to the drill bit body 13 by a first locking means in the form of laterally extending pins 14 and 15. These pins partially extend into openings in the wall of the collar of the whipstock 11 as will become clearer as the description proceeds. The whipstock is also locked to the drill bit body 13 for rotation therewith by a plurality of splines 16 and 17 formed on the exterior surface of the drill bit body.

With particular reference to FIGURE 2, four such splines as shown at 16 and 17 by way of illustration are provided equally circumferentially spaced about the drill bit body 13. The inner collar portion of the whipstock 11 includes grooves such as indicated at 18 and 19 for receiving these splines. In the relative longitudinal positions of the drill bit body 13 and whipstock 11, as shown, it will be evident that the whipstock 11 is locked against rotation relative to the drill bit body 13 by the splines, but may move longitudinally with respect thereto once the locking pins 14 and 15 are released.

Drilling fluid such as mud is passed through a mud passage 20 (FIGURE 2) in the drill bit body 13 and then diverted as will be described in greater detail to a fluid passage 21 illustrated in dotted lines in the whipstock tool 11. This fluid passage divides and terminates at a pair of cutting wheels, one of which is shown in the view of FIGURE 1 at 22. These cutting wheels serve the same function as a drill bit and as the whipstock 11 is being lowered into the bore hole 10, drilling fluid will normally be circulated through the passage 21 in the whipstock.

In FIGURE 3, the locking pins 14 and 15 are shown blown laterally into the surrounding formations so that the drill bit body 13 is free to move longitudinally through the whipstock 11. Thus, as illustrated, the drill bit body 13 has been moved free of the whipstock so that the splines 16 and 17 are free of the grooves in the whipstock and the drill bit 13' is free to rotate with the whipstock 11 held in a stationary position to perform its conventional deflecting operation. In the lower portion of FIGURE 3, it will be noted that the drill bit 13' has been employed to form a deflected bore or "rathole" 23.

After the rathole 23 has been formed, which is of smaller diameter than the bore 10, the drill pipe string 12 and drill bit body 13 are retracted back up through the whipstock. At this point, a second locking means in the form of an annular channel 24 formed in the extreme upper portion of the drill bit body 13 and illustrated in dotted lines in FIGURE 4 is arranged to receive locking pins 25 and 26 biased laterally inwardly and formed in the upper portion of the whipstock 11. Thus, the drill bit body 13 is again locked to the whipstock by the annular channel 24 receiving the biased pins 25 and 26 and also by registration of the splines 16 and 17 with corresponding grooves in the whipstock.

After this operation has been completed as shown in FIGURE 4, the entire drill pipe string 12 may be rotated, thereby rotating the whipstock 11 so that this whipstock tool then functions as a reaming tool, the cutting wheels 22 reaming out the rathole 23.

FIGURE 5 shows a subsequent position of the whipstock tool 11 after a major portion of the reaming operation has been completed as indicated at 27. When the deflected bore 23 has been completely reamed out, the entire drill pipe string 12 is removed along with the whipstock 11 from the bore hole and conventional drilling bits secured to the end thereof and drilling them commenced through the reamed out deflected bore 27 in a conventional manner.

From the foregoing, it will be evident that a trip in and out of the bore hole has been avoided by the deflection method and apparatus as described since the whipstock tool itself has been employed both as a deflected tool and as a reaming tool. Thus, it is not necessary to remove the entire drill pipe string after the "rathole" has been formed and remove the whipstock and then replace it with a reaming tool.

In the foregoing operation, it is necessary that drilling fluid be passed out the end of the drill bit 13 when the "rathole" is being formed as depicted in FIGURE 3. On the other hand, it is necessary that this drilling fluid be diverted and passed through the whipstock fluid passage 21 when the whipstock is being used as a drilling tool. The method and apparatus for diverting the drilling fluid in this manner as well as the operation of the locking means and other features of the invention will be evident by now referring to FIGURES 6, 7, and 8.

Referring first to FIGURE 6, it will be noted that the first locking means in the form of the pins 14 and 15 extend laterally from the drill bit body 13 within lateral openings 28 and 29 formed in the whipstock tool 11. It will be evident that when the pins 14 and 15 are in the position shown in FIGURE 6, the whipstock and drill bit body 13 are locked against relative longitudinal movement.

In this position, the fluid passage 20 communicates with a cylindrically shaped plunger 30 positioned in the drill bit body 13 and provided with lateral openings such as 31. These openings are in registration with lateral openings 32 in the drill bit body 13. Lateral openings 32 in turn communicate with a first annular passage 33 formed on the inside wall of the whipstock tool 11 and connecting with the fluid passage 21 in the whipstock. Fluid seals are provided by O-rings 34 and 35 spaced below and above, respectively, the annular fluid passage 33 so that fluid passing through the lateral openings 31 in the plunger 30 and openings 32 in the drill bit body 13 will be forced out the fluid passage 21 in the whipstock.

With reference still to FIGURE 6, it will be noted that the lower end of the plunger 30 includes angulated fluid openings 36 passing into a chamber, the lower end of which terminates in a valve seat 37. The under side of the valve seat 37 is closed off by a valve head 38 rigidly secured to the lower end of the plunger 30 as shown. A spring 39 normally biases the plunger upwardly so that the valve head 38 is seated on the valve seat 37, thereby blocking fluid received within the plunger 30 from passing through the angulated openings 36 and past the valve seat 37. A pin 40 engages the underside of the valve head 38 to provide a positive lock against any possible downward movement of the plunger 30 and opening of the valve seat 37 when the pin 40 is in the lateral inward position illustrated. Normally, this pin 40 is biased in an outward direction by a tension spring 41. However, it is prevented from moving laterally outwardly by the engagement of its exterior end with the inside wall of the whipstock 11. Thus, so long as the drill bit body 13 is locked to the whipstock, drilling fluid necessarily passes in the direction of the arrows shown in FIGURE 6 and thus will flow down the whipstock passage 21.

When the drill bit body 13 is free of the whipstock such as depicted in FIGURE 3, the lateral pin 40 is free to move outwardly when pulled by the tension spring 41 since the extreme end thereof is no longer in engagement with the inside surface of the whipstock. Under these conditions, as shown in FIGURE 7, the valve head 38 may move downwardly against the force of the spring 39. This initial downward movement is effected by simply increasing the mud pressure after the drill bit body has been lowered through the whipstock so that downward movement of the plunger 30 will cause the lateral openings 31 to move out of registration with the lateral

openings 32, thereby blocking any flow of drilling fluid out through the lateral openings 32 of the drill bit body. The fluid flow will thus be in the direction of the arrows shown in FIGURE 7 down past the valve seat 37 and to the drill bit 13'.

When now the drill bit body 13 is retracted into the whipstock tool 11 into a second longitudinal position as depicted in FIGURE 4, the laterally biased pins 25 and 26 illustrated in detail in the upper view of FIGURE 8 will be received within the annular channel 24 at the upper end of the drill bit body 13, thereby locking the drill bit body 13 to the whipstock against any longitudinal movement relative thereto. The pins 25 and 26 are at all times biased radially inwardly so that they will automatically be received within the annular groove 24 when the drill bit body 13 assumes its second position.

In the position shown in FIGURE 8, it will be noted that the lateral openings 32 are brought into registration with a second annular fluid passage 33' in the whipstock 11. It will also be noted that the plunger 30 has returned to its upper position. This return of the plunger is effected by the spring 39 when the mud pressure is lowered after the drilling of the "rathole" has been completed. Further, as the drill bit body 13 is retracted into the whipstock, the pin 40 will be biased inwardly by the inside surface of the whipstock to lock under the valve head 38 and thus positively hold the plunger 30 in its upward position as shown in FIGURE 8.

From the foregoing, it will accordingly be clear that drilling fluid is always diverted through the whipstock passage 21 whenever the drill bit body 13 is in its first position as shown in FIGURE 6 or in its second position as shown in FIGURE 8. The only time that drilling fluid will be passed directly to the drill bit 13' will be when the drill bit body 13 is free of the whipstock 11.

In addition to the foregoing method and apparatus of deflection drilling, the instant invention also contemplates a novel orienting method and apparatus for initially positioning the whipstock in order that the deflected bore may be initiated in a desired direction. This orienting apparatus is indicated generally by the numeral 42 in both FIGURES 6 and 8 and in the cross section of FIGURE 9. Essentially, the structure includes an annular groove of semicircular shape in cross section as indicated at 43. The open face of this groove is directed upwardly and is adapted to receive a conducting ball 44. The ball 44 is free to roll to any circumferential position in the groove 43 and will normally seek a position corresponding to the low side of the bore hole.

As illustrated best in FIGURE 9, the bottom of the annular groove 43 includes a continuous contact in the form of an annular brass ring 45, which contact is always in engagement with the ball 44. Also provided is a second circumferentially adjustable contact 46 which may be preset to any desired circumferential position on the orienting structure 42.

Two additional contacts 47 and 48 are provided in the fluid passage bore 20 as illustrated in FIGURES 6 and 8, these additional contacts being connected in series with the contacts defined by the brass annular ring 45 and the circumferentially adjustable contact 46.

With particular reference to FIGURE 9, there is schematically shown a source of electrical energy in the form of a battery 49 connected by a lead 50 to the second contact 48 and also to an explosive charge 51. A return lead 52 extending from the explosive charge 51 in turn connects to the circumferentially adjustable contact 46. The wiring is such that when the ball 44 assumes a position to engage the contact 46 it will connect this contact to the annular brass ring 45 thereby closing these two contacts. If now the additional contacts 47 and 48 are connected together, a circuit will be completed through the battery to detonate the explosive charge 51.

In the operation of the overall system, the whipstock 11 is assembled to the drill bit body 13 at the surface

of the bore hole. The spline and groove connections will prevent relative rotation of the whipstock 11 with respect to the drill bit body 13 as already described and the partially extending pins 14 and 15 will in turn prevent relative longitudinal movement between the whipstock 11 and drill bit body 13. Assume, for the sake of illustration, that if it is desired to deflect the hole 10 to the right such as indicated in FIGURES 1, 3, 4, and 5. It is first assumed that a slight deflection to the right has already occurred with respect to the bore hole 10 so that the lefthand wall of the bore hole represents the low side of the hole. In order that the whipstock 11 be oriented in the position illustrated in FIGURES 1, 3, 4, and 5 to deflect the drill bit to the right, the circumferentially adjustable contact 46 will be positioned on the orienting apparatus 42 so that the rear side of the whipstock 11 falls directly underneath the contact. In other words, when the contact 46 is in the position illustrated in FIGURE 9, the open face of the whipstock will be directed to the right as indicated by the arrow.

After the foregoing adjustment has been made and the whipstock secured to the drill bit body, the whipstock and drill bit body are lowered on the end of the drill pipe string into the bore hole 10. During this operation, drilling fluid is passed through the drill pipe string 12 and internal fluid passage 20 of the drill bit body 13 and thence out the lateral openings 31 and 32 in the plunger and drill bit body 13 to the mud passage 21 as described so that this fluid will circulate out the end of the whipstock.

When the whipstock engages the bottom of the bore hole or the point in the bore hole at which a deflection is to be made, the operator at the surface of the bore hole will drop the conducting bar or equivalent object 53 through the drill pipe string so that it will close the contacts 47 and 48. Unless the ball 44 happens to be in engagement with the contact 46, nothing will occur. The operator will then rotate the kelley fifteen degrees and then wait for five seconds or so until the ball 44 has a chance to come to rest in a position corresponding to the low side of the hole. The contact 46 will not be at the low side of the hole unless the whipstock 11 is facing in the desired direction which is away from the low side of the hole. Thus, the drill bit body may continue to be rotated in fifteen degree steps until the ball 44 bridges the contact 46 with the annular brass ring 45. At this point, the circuit will be complete through the battery 49 and the explosive charges 51 will be detonated causing the pins 14 and 15 to be exploded laterally outwardly and free the drill bit body from the whipstock.

After the drill bit body 13 is released from the whipstock, the entire drill pipe string is lowered through the whipstock and the deflection drilling carried out as described in conjunction with FIGURE 3. When the drill bit body 13 is free of the whipstock, the pin 40 will be free to move laterally outwardly and will release the plunger 30 so that fluid flow can then take place through the drill bit 13' as described theretofore.

The rathole 23 described in conjunction with FIGURE 3 is then formed and thereafter the drill pipe string is raised to raise the drill bit body 13 back into the whipstock. The drill pipe string may be rotated slightly in order to effect registration of the splines and grooves and when registration is made, the drill bit body may be retracted further to its second position wherein the spring biased pins 25 and 26 will be received within the annular channel 24. This latter second position has already been described in conjunction with FIGURE 8. In this position, it will be evident that the drill bit body is again locked to the whipstock both against longitudinal movement and rotational movement relative thereto. Also, in this second position, it should be noted that the plunger 30 is in its raised position so that fluid will again be passed through the passage 21 in the whipstock.

The entire drill pipe string may then be rotated and the whipstock 11 employed as a reaming tool as described.

in conjunction with FIGURES 4 and 5. During this reaming operation, fluid flow will be through the whipstock.

Finally, when the rathole has been completely reamed out, the whipstock and drill bit body are raised to the surface of the bore hole and conventional drilling equipment substituted therefor. The deflected bore may then continue to be drilled in a conventional manner.

From the foregoing description, it will be evident that the present invention has provided a method and apparatus in which a round trip in and out of the bore hole has been completely avoided. Accordingly, a considerable savings in time, labor, and expense is realized.

While only one form of the invention has been shown and described, it will be evident to those skilled in the art that many equivalent components and steps could be employed. The method and apparatus are therefore not to be thought of as limited to the exact steps and structure set forth merely for illustrative purposes.

What is claimed is:

1. A method of deflection drilling with a whipstock, including the steps of: lowering said whipstock on the end of a drill bit body connected to a pipe string; orienting the position of said whipstock by rotating said pipe string to rotate said whipstock so that said deflection drilling will extend in a pre-determined direction; releasing said whipstock from said drill bit body; urging said drill bit body through said whipstock to drill a deflected hole while said whipstock is stationary; circulating drilling fluid through said drill bit body during the drilling of said deflected hole; pulling up on said drill bit body to re-engage said whipstock; locking said whipstock to said drill bit body for rotation and longitudinal movement therewith; diverting said drilling fluid to pass through said whipstock; and rotating and lowering said whipstock by said drill pipe string to ream out said deflected hole throughout substantially its entire length with said whipstock functioning as a drill bit.

2. An apparatus for use with a drill bit body and drill bit on the end of a drill pipe string, comprising, in combination: a whipstock tool having cutting wheel means adjacent to its lower end; means for locking said whipstock tool to said drill bit body; means for releasing said whipstock tool from said drill bit body so that drilling may proceed to form a deflected hole with said whipstock tool in a stationary position to guide said drill bit body; and means for relocking said whipstock tool to said drill bit body so that said cutting wheel means on said whipstock tool can be used as a drilling tool to ream out said deflected hole throughout substantially the entire length of said deflected hole, said whipstock tool including a drilling fluid passage and said drill bit body including fluid flow control means for diverting drilling fluid into said fluid passage when said whipstock tool is locked to said drill bit body and for directing fluid out said drill bit when said drill bit body is free of said whipstock.

3. An apparatus for deflection drilling for use with a drill bit body and drill bit secured to the end of a pipe string, comprising, in combination: a whipstock tool having a fluid passage therein and cutting wheel means adjacent to its lower end; coupling means comprising longitudinal splines and grooves on said drill bit body and whipstock tool respectively for coupling said whipstock tool to said drill bit body for rotation therewith; first locking means for securing said whipstock tool to said drill bit body for longitudinal movement therewith when said drill bit body is in a first longitudinal position relative to said whipstock tool; releasing means for said first locking means; second locking means responsive to a second longitudinal position of said drill bit body relative to said whipstock tool for securing said whipstock tool to said drill bit body for longitudinal movement therewith, said splines and grooves locking said drill bit body and whipstock tool for rotation together when said drill bit body is in said first longitudinal position and said second longitudinal position; and drilling fluid flow control means in

5 said drill bit body for diverting drilling fluid from said drill pipe string to said fluid passage in said whipstock tool when said drill bit body is in said first and second longitudinal positions and for blocking fluid from said fluid passage in said whipstock tool and passing said fluid down through said drill bit body to said drill bit when said drill bit body is free of said whipstock tool, whereby a deflected hole may be drilled by said drill bit after releasing said first locking means so that said whipstock tool is stationary and guides said drill bit in a given direction, and whereby said drill bit body may be retracted to re-engage said whipstock tool when said drill bit body is in said second position so that said whipstock tool may be rotated and lowered into said deflected hole to cause said cutting wheel means to ream out said deflected hole throughout substantially its entire length.

4. An apparatus according to claim 3, in which said first locking means comprises pins extending laterally from said drill bit body, said whipstock tool having lateral openings for receiving the exposed ends of said pins.

5. An apparatus according to claim 4, in which said releasing means includes explosive charges positioned in said drill bit body behind said pins; and means for detonating said charges to blow said pins laterally completely through said openings in said whipstock tool.

6. An apparatus according to claim 3, in which said second locking means includes an annular channel formed about said bit body and laterally biased locking pins on said whipstock tool adapted to snap into said channel when juxtaposed thereto, said second longitudinal position bringing said channel and pins into juxtaposition, said drill bit body being in a higher position relative to said whipstock tool when in said second position than when in said first position.

7. An apparatus according to claim 3, in which said drilling fluid control means includes a plunger having lateral openings and disposed within said drill bit body, said drill bit body having lateral parts communicating with said fluid passage in said whipstock tool and registering with said lateral openings in said plunger when said plunger is in a first position; means holding said plunger in said first position, said means being responsive to disengagement of said drill bit body from said whipstock tool to release said plunger to move to a second position and thereby move said lateral openings in said plunger out of registration with said lateral openings in said drill bit body and whipstock tool to block fluid flow through said lateral openings, said plunger including a valve head blocking passage of fluid to said drill bit when said plunger is in said first position and permitting passage of fluid to said drill bit when said plunger is in said second position.

8. An apparatus according to claim 5, including orienting means in said drill bit body comprising: an annular groove semi-circularly shaped in cross-section with its open face directed upwardly; a conducting ball adapted to roll in said groove; an annular contact in engagement with said ball at all times; a circumferentially adjustable contact positionable to be engaged by said ball when in a given circumferential position defined by the lower side of said bore hole; additional contacts in series with said annular and circumferentially adjustable contacts; and an electrical source connected to said explosive charges through said contacts so that said explosive charges will be detonated when said ball is in said given circumferential position and said additional contacts are closed to release said whipstock tool.
